UNITED STATES PATENT OFFICE.

CARRIE E. SNAVELY, OF SAUK RAPIDS, MINNESOTA.

HEATING ATTACHMENT FOR LAMP-CHIMNEYS.

1,144,920.

Specification of Letters Patent. Patented June 29, 1915.

Application filed December 29, 1914. Serial No. 879,498.

To all whom it may concern:

Be it known that I, CARRIE E. SNAVELY, a citizen of the United States, residing at Sauk Rapids, in the county of Benton and 5 State of Minnesota, have invented certain new and useful Improvements in Heating Attachments for Lamp-Chimneys; and I do hereby declare the following to be a full, clear, and exact description of the invention 10, such as will enable others skilled in the art to which it appertains to make and use the same.

This invention has for its object to provide a novel and inexpensive heating attachment which may be readily applied to 15 and supported upon a lamp chimney for the purpose of utilizing the heat generated by the illuminating flame.

Another object is the provision of an attachment of this character including a body having an annular flange or shelf at its lower edge constituting a combined support 20 for objects placed thereon and a reflector for the lamp.

Another object is the provision of a heating attachment for lamp chimneys including a frusto-conical body portion having a perforate drum at the upper end for radiating the heat rising through the chimney.

With these and other objects in view, the invention consists in the novel construction, arrangement and formation of parts as will be hereinafter specifically described, claimed and illustrated in the accompanying drawings, in which the figure represents a longitudinal sectional view through the attachment applied to use.

Referring to the drawing by numerals of reference, the numeral 5 indicates the frusto-conical body of the attachment preferably stamped from sheet metal and having an angularly directed and horizontally disposed flange or shelf 6 of annular formation projecting from the lower edge thereof. A shank 7 is secured to the frusto-conical body 5 and carries a handle 8 at its outer extremity whereby the attachment may be conveniently positioned upon or removed

from a lamp chimney 11. A hollow drum of considerably greater diameter than the 50 upper extremity of the frusto-conical member 5 is secured to the latter and formed with a plurality of perforations 10. As clearly illustrated in the drawing, the bottom of the drum 9 is formed with an opening 55 in which is received the upper edge of the frusto-conical body 5.

In use, the frusto-conical body 5 of the attachment is positioned over the upper end of the lamp chimney 11, and the heat rising 60 within the chimney is radiated by the drum 10. It is evident that the annular flange or shelf at the lower edge of the frusto-conical body is so arranged as to support articles in position adjacent the lamp chimney 65 and also constitutes a reflector for reflecting the rays of light from the flame of the lamp.

What I claim is:

1. An attachment for lamp chimneys comprising a frusto-conical body, an annular 70 flange or shelf at the lower end of said body, and a perforate drum at the upper end of said body.

2. An attachment for lamp chimneys comprising a frusto-conical body, an annular 75 flange secured to the large end of said body, and a perforate drum secured to the small end of said body.

3. An attachment for lamp chimneys comprising a frusto-conical body, an annular 80 flange or shelf secured at the large end of said body and a perforate drum secured to and of greater diameter than the small end of said frusto-conical body.

4. An attachment for lamp chimneys comprising a frusto-conical body, an annular flange at the large end of said body, a perforate drum at the small end of said body, and a handle carried by said frusto-conical body. 85

In testimony whereof I affix my signature 90 in presence of two witnesses.

CARRIE E. SNAVELY.

Witnesses:

OLIVER CHIRHATT,
ADELBERT J. OLIVER.
